RAILWAY CAR MOVING APPARATUS

Robert H. Pill, Elgin, Ill., assignor to himself and
Harold Hoffman, Elgin, Ill.

Application August 10, 1945, Serial No. 610,145

13 Claims. (Cl. 105—141)

1

This invention relates to railway car moving apparatus, and particularly the invention relates to apparatus of the aforesaid character adapted for pushing or imparting relatively slow movement to railway cars while such cars are located on sidings at loading platforms, or in and about manufacturing plants, or in other similar situations where a conventional switching locomotive is not readily available.

Where such movements of railway cars have been required it has heretofore been customary to utilize a car pusher in the form of an elongated hand lever having a forward operating end or element associated therewith and adapted to be wedged into the acute angular space between a car wheel and the rail upon which such wheel is supported, and by downward movement of the hand lever, the operator causes the operating end or element of the car pusher to impart an upward and forward force to the wheel to thereby cause forward rolling movement of the wheel. The operator then raises the hand lever and forces the forward element of the car pusher forwardly along the rail so as to reestablish the operative relation between the car pusher and the car wheel, and by another downward movement of the operating handle another forward rolling force may be applied to the wheel. Thus by repeated up and down movements of the operating handle, coupled with appropriate forward movements of the pusher to repeatedly reestablish the operative relationship with the wheel, an operator with the conventional car pusher is able to attain the desired movements of a railway car, but such movements of the railway car are relatively slow, and involve extreme physical exertion, particularly where the cars are heavily loaded or where the siding or track is inclined or curved.

In view of the foregoing it is the primary object of the present invention to simplify the pushing or moving of railway cars on sidings and the like, and to enable such car movements to be attained rapidly and with very little physical exertion. Further and related objects of the invention are to enable a car pusher to apply a continuous forward rolling force to the wheel of a car so as to attain a continuous forward movement of the cars, to automatically maintain such a car pusher in an operative relationship with respect to the car wheel as the forward rolling movement of the car wheel progresses, and to enable such a car pusher to be embodied in a relatively portable form that includes power driven means for applying the requisite forces between the car wheel and the rail.

2

Other and further objects of the present invention will be apparent from the following description. In the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a side elevational view of a car pusher embodying the features of the invention;

Fig. 2 is a vertical sectional view taken along the line 2—2 of Fig. 1;

Fig. 3 is a plan view taken partially in section to illustrate details of internal construction;

Fig. 4 is a fragmental vertical section taken on the line 4—4 of Fig. 3;

Fig. 5 is a plan view; and

Fig. 6 is an elevational view of the other side of the car pusher.

In the form chosen for disclosure herein the invention is embodied in a power operated car moving apparatus or car pusher 10 that is portable in character and is adapted to be supported and guided on a railway rail R so as to be disposed in the rearwardly facing acute angular space between a rail R and the tread T of a wheel W supported on the rail, and when the car pusher 10 is thus positioned it is effective to impart forward rolling forces to the wheel W to thereby cause the desired forward movement of the railway car that is carried in part by such wheel. The car pusher 10 has its operating mechanisms carried by a main frame 12 which, as shown in Fig. 1, is generally triangular in side elevation so as to thereby enable the frame to be accommodated in the acute angular space that is available between the rail R and the wheel W, and the narrow forward end or extension 12F of the frame 12 serves as a mounting for a force applying or tractive unit 14 for operative engagement with the wheel W and the rail R to impart forward rolling movement to the wheel W and at the same time advance the car pusher 10 along the rail to maintain the desired operative relationship with the wheel W. The forward end of the frame 12 is supported and guided on the rail R by elements of the tractive unit 14, as will hereinafter become evident, while the rear end of the frame 12 is supported on the rail R by a roller 16 disposed near the rear end of the

frame, and in the use of the car pusher 10, its position and operation may be controlled and governed by the operator by means of a handle 18 that extends upwardly and rearwardly from the frame 12 so that it may be grasped and held by the operator during operation of the car pusher.

In the present instance the tractive unit 14 of the car pusher 10 is driven by power means in the form of an electric motor 20 that is mounted on one side of the frame 12 as to project laterally therefrom, and the weight of the motor 20 is substantially counterbalanced by a lateral extension 22, that projects from the opposite side of the frame, as shown in Figs. 3 and 5, and which serves as a housing for a part of the power transmission means between the motor 20 and the tractive unit 14. In practice the electric power for the motor 20 is supplied by an electric cord 24 that extends into the end of the handle 18 as shown in Fig. 1, and the handle is preferably tubular in character so that the cord 24 may extend downwardly therethrough to a point adjacent the frame 12 where it is led outwardly through a side opening 26 and is connected to the motor 20. Near the upper end of the handle 18 a control switch 28 is mounted inside of the handle, and is interposed electrically in the cord 24, and by manipulation of a projecting switch handle 28A, the user may start and stop the motor 20 as required in the use and control of the car pusher.

As will be evident in Figs. 3 and 5, the frame 12 is constructed in the form of a sectional housing that affords an enclosure as well as mounting means for the elements of the transmission gearing between the motor 20 and the tractive unit 14, and to this end, the frame 12 comprises a main housing section 12A having a side wall 12B and edge flanges or walls 12C about the edges thereof to thereby define a gear chamber 12D that is closed by a side or cover plate 12E. Fastening bolts 29 are extended through the housing section 12A and into the cover plate 12E to secure the same in position on the section 12A. The main housing section 12A has a projecting mounting base or flange 30 extended from the outer side thereof to receive and interlock laterally with the flanged end of the casing of the motor 20, and fastening bolts 32 extended through the motor casing are threaded into the flange 30 so as to hold the motor 20 in place on the housing section 12A.

When the motor 20 is thus secured in place the motor shaft 20A extends through an opening 34 in the side wall 12B of the housing section 12A so that a drive pinion 36 on the end of the motor shaft 20A is disposed within the gear chamber 12D. The pinion 36 that is thus located within the gear chamber 12D is operative to drive a speed reducing and motion transmitting gearing that is housed in part within the gear chamber 12D and in part within the extension 22 of the frame 12, and such gearing terminates in a drive shaft 40 that is supported in the extension 22 and is operatively connected to the tractive unit 14 in a driving relation as will hereinafter be described in detail. In effecting such driving connection between the drive shaft 40 and the tractive unit 14, the drive shaft 40 is so disposed that a splined end 40A thereof is located within the forward frame extension 12F and outside of the forward edge wall 12C of the housing section 12A, and to afford such a location for the shaft 40, the extension 22 is formed on the cover plate 12E in a forward position as 75

shown in Figs. 3, 5 and 6. Thus, the extension 22, as herein shown, comprises a first tubular section 22A opening through the plate 12E into the gear chamber 12D and a second tubular section 22B formed on the plate 12E so as to open through the plate at a point forwardly of the forward edge wall 12C of the housing, and the projecting ends of the tubular sections 22A and 22B are closed by a hollow and generally cup-shaped cap 22C that abuts a flange 22F formed about the ends of the tubular sections 22A and 22B, and the cap 22C is held in place by screws 42.

The drive shaft 40 is rotatably supported in the tubular section 22B by a bearing sleeve 44 and near the end thereof a gear 45 is fixed on the shaft 40 so as to be disposed within the cap 22C, the extending end 40B of the shaft 40 being supported in the cap 22C by a bearing sleeve 46. The tubular section 22A serves to support a transmission shaft 50 by means of a bearing sleeve 52, while a bearing sleeve 54 in the cap 22C rotatably supports the end 50B of the shaft 50, and between the two bearings 52 and 54, the shaft 50 is splined as at 50A and has a gear 55 engaged with the splines 50A and housed within the cap 22C. The gears 45 and 55 are operatively connected by an idler gear 57 disposed within the cap 22C and fixed on a supporting stub shaft 58. One end of the stub shaft 58 is rotatably supported on a bearing sleeve 57 in the cap 22C, while a bearing sleeve 60, mounted in a web 22W that connects the ends of the tubular sections 22A and 22B, serves to support the other end of the stub shaft 58.

The transmission shaft 50 is arranged to extend into the gear chamber 12D, and within this chamber a gear 65 is fixed so that a speed reducing gearing may be afforded within the chamber 12D between the drive pinion 20A and the gear 65. Such speed reducing gearing is in the present case afforded by a series of interconnected gears and pinions supported within the housing or chamber 12D by three parallel shafts 66, 67 and 68, the opposite ends of which are rotatably supported by appropriate bearings, such as bearing bosses 69, provided on the side wall 12B and the cover plate 12E. The shaft 66 has a large gear 66G and a small pinion 66P fixed thereon so that the gear 66G is meshed with the drive pinion 36, while the shaft 67 has a large gear 67G and a small pinion 67P fixed thereon so that the gear 67G meshes with the pinion 66P. Similarly, the shaft 68 has a large gear 68G and a small pinion 68P fixed thereon, and the gear 68G is meshed with the pinion 67P while the pinion 68P is meshed with the gear 65. Thus a substantial gear reduction is afforded whereby the drive shaft 40 is driven at a slow speed that is suitable for operation of the tractive unit 14.

As hereinbefore pointed out, the tractive unit 14 is supported by the forward extension 12F of the frame 12 of the device, and as will be apparent in the drawings, the extension 12F of the frame is sectional in character and is formed in part by a forward extension of the cover plate 12E of the gear housing. Thus this forward extension 12F acts as one bearing plate and serves as a support for a parallel but spaced bearing plate 70 so that the operating or force applying elements of the tractive unit 14 may be supported between such bearing plates. The force applying elements of the tractive unit 14 are in the present case afforded by three toothed wheels 71, 72 and 73 that are rotatably mounted between the bearing plates 12F and 70, and the two bearing plates

are separably related to enable such toothed wheels to be mounted in position therebetween. Thus the forward ends of the bearing plates 12F and 70 have end walls 75 extended toward each other and terminating in flanges 76 through which fastening bolts 77 are extended, while adjacent the forward wall 12C of the housing, the plates 12F and 70 have opposed tubular bosses 78 arranged so their inner ends abut each other, and a fastening bolt 79 is passed through the bosses 78 to secure the plate 70 on the plate 12F.

The mounting space that is thus afforded between the plates 12F and 70 is arranged to be open at its upper and lower sides, and the toothed wheels 71 and 73 are arranged so that their lower edges extend out of the open lower side of the mounting space, while the upper surface of the toothed wheel 72 extends outwardly through the open upper side of the mounting space. The wheels 71 and 73 are therefore positioned so as to ride upon the upper surface of the rail R, and the desired guiding of the forward end of the machine is accomplished by a downwardly projecting guide lug 83 formed respectively on the lower edge of the plate 70 and on the tubular portion 22B, and a pair of downwardly projecting lugs 81 on the lower edge of the plate 12F. The lugs 80 and 81 are thus disposed so as to extend downwardly along opposite side edges of the rail R, and hence the tractive unit 14 is maintained in the proper lateral relation to the rail R and the wheel W. In supporting the toothed wheels 71, 72 and 73 in the desired relationship between the plates 12F and 70, the toothed wheel 71 is internally splined and is mounted on the splined portion 40A of the drive shaft 40, the reduced end 40C of this shaft being supported in a bearing sleeve 83 in the plate 70. The wheel 71 is thus located near the rear end of the tractive unit 14, and the toothed wheel 73 is supported in spaced relation thereto and near the front of the unit 14 on a shaft 84 that is embodied as a tie bolt having a head 84A and a nut 84B so as to thereby afford additional means holding the mounting or bearing plates 12F and 70 together. The other toothed wheel 72 is mounted on a stub shaft 85 so that the ends of the shaft extend beyond the ends of the wheel 72 and are loosely supported in retaining pockets or bores 86, Fig. 3, formed in the bearing plates 12F and 70.

The arrangement of the toothed wheels 71, 72 and 73 is such in the present instance that the teeth of the wheel 72 rests upon and meshes with the teeth of the wheels 71 and 73 so that the wheel 72 acts as an idler or transmitting connection between the wheel 73 and the wheel 71. Thus when the shaft 40 is driven in the direction indicated by the arrow in Fig. 4, so as to thereby advance the car pusher in a forward direction toward a wheel W, the wheel 73 will be similarly driven in such a direction as to also have a similar forward driving action. At the same time and as an incident to such forward advancing movement of the car pusher, the upper toothed wheel 72 is driven in the opposite direction as indicated by the arrow on the wheel 72 in Fig. 4, and hence when the exposed upper surface of the wheel 72 engages the tread of the wheel W, it will tend to impart forward rolling movement to the wheel W as indicated by the arrow applied to the wheel in Fig. 4.

Since the teeth of the several wheels 71, 72 and 73 are in the present instance arranged to function both as power transmitting gears and as frictional elements for drivingly engaging the

smooth surfaces of the rail R and the wheel W, such teeth are of a modified form such that relatively sharp edges are presented for engagement with the rail and the wheel. The relatively loose mounting of the upper toothed wheel 72 enables the reaction of the car wheel W to press the teeth of the wheel 72 downwardly into positive engagement with the teeth of the other wheels 71 and 73, and hence the driving connection therebetween becomes more positive as the load increases.

In the use of the car pusher that is thus afforded, the device is placed in position on the rail R adjacent to a wheel W of a railway car that is to be moved, and is held in an upright position by means of the rearwardly extending handle 18. When the car pusher is thus positioned the wheels 71 and 73 support the front end thereof on the rail, while the roller 16 supports the rear end thereof, and the lugs 80 and 81 serve to locate and guide the forward end of the device in a lateral sense on the rail. The operator may then actuate the switch lever 28A to start the motor 20, and the wheels 71 and 73 of the tractive unit will be started so as to advance the car pusher forwardly toward the adjacent wheel W. The car pusher will thus advance into the acute angular space between the rail and the wheel, and if it happens that the extension 22 is disposed on the inner side of the rail so as to be aligned with the flange of the wheel W, it will be observed that adequate clearances are afforded, as will be evident in Figs. 2 and 3.

As such forward movement of the car pusher progresses, the toothed wheel 72 will of course engage the tread of the wheel W, and when this occurs, the combined forward driving action of the wheels 71 and 73 and the upward driving action of the wheel 72 on the car wheel W will impart forward rolling movement to the car wheel W. The driving action is of course continuous, and since the three toothed wheels 71, 72 and 73 are in effect wedged into the angular space between the car wheel and the rail by the forward driving action of the wheels 71 and 73, the frictional driving contact of the toothed wheels with the rail and the car wheel becomes greater as the resistive load increases. Thus the car moving operation of the present car pusher is efficient insofar as the power or force applying action is concerned, and since the car pusher follows the advancing movement of the car, the forward movement of the car is continuous, and repeated starting and stopping of the car is avoided so as to eliminate waste of time and power.

From the foregoing description it will be apparent that the present invention materially simplifies the problem of pushing or moving railway cars on sidings or the like, and since the car pusher provided by the present invention is portable in character and is power operated, the desired car movements may be attained without appreciable physical exertion. The present invention provides for a constant advancing movement of the car pusher as the car rolls along the track, and hence the efficiency of operation of the device is relatively great. The car mover of the present invention is particularly advantageous in that the desired car movements may be rapidly accomplished, so that loss of loading or unloading time is avoided.

Thus, while I have illustrated and described the preferred embodiment of my invention, it is to be understood that this is capable of variation and modification and I therefore do not wish to

be limited to the precise details set forth, but desire to avail myself of such changes and alterations as fall within the purview of the following claims.

I claim:

1. In a portable car moving apparatus adapted to be disposed in an operative position in the acute angle between a railway rail and a car wheel for operative engagement with the wheel and rail to impart rolling movement to such wheel, a portable supporting frame having guide means on the lower portions thereof for engaging the top side edges of such a rail to support and guide said frame along said rail, an upper driving element rotatably mounted on said frame for driving engagement with the rim of such a wheel to impart forward rolling movement thereto as said frame advances in a forward direction along the rail, a plurality of lower driving elements rotatably mounted on said frame and arranged for driving engagement with said rail to advance said frame forwardly on said rail, a guiding and manipulating handle extended rearwardly and upwardly from said frame, a driving motor mounted on and extending laterally from one side of said frame, and driving gearing on said frame driven by said motor and including speed reduction means, said gearing being disposed so as to extend at least in part from said frame in the opposite lateral direction to said motor to thereby substantially counterbalance the weight of said motor, and said gearing being operatively connected to said upper and lower driving elements to drive the same in opposite rotative directions for simultaneously advancing the apparatus and rotating the wheel.

2. In a portable car moving apparatus adapted to be disposed in an operative position in the acute angle between a railway rail and a car wheel for operative engagement with the wheel and rail to impart rolling movement to such wheel, a portable supporting frame having guide means on the lower portions thereof for engaging the top side edges of such a rail to support and guide said frame along said rail, an upper driving element rotatably mounted on said frame for driving engagement with the rim of such a wheel to impart forward rolling movement thereto as said frame advances in a forward direction along the rail, a plurality of lower driving elements rotatably mounted on said frame and arranged for driving engagement with said rail to advance said frame forwardly on said rail, a guiding and manipulating handle extended rearwardly and upwardly from said frame, a driving motor mounted on and extending laterally from one side of said frame, driving gearing on said frame driven by said motor and including speed reduction means, said gearing being disposed so as to extend at least in part from said frame in the opposite lateral direction to said motor to thereby substantially counterbalance the weight of said motor, and said gearing being operatively connected to said upper and lower driving elements to drive the same in opposite rotative directions for simultaneously advancing the frame and rotating the wheel, and control means for said motor disposed on said handle in a position wherein it is readily accessible to the user.

3. In a portable car moving apparatus adapted to be disposed in an operative position in the acute angle between a railway rail and a car wheel for operative engagement with the wheel and rail to impart rolling movement to such

wheel, a portable supporting frame having guide means on the lower portions thereof for engaging the top side edges of such a rail to support and guide said frame along said rail, an upper driving element rotatably mounted on said frame for driving engagement with the rim of such a wheel to impart forward rolling movement thereto as said frame advances in a forward direction along the rail, a plurality of lower driving elements

5 rotatably mounted on said frame and arranged for driving engagement with said rail to advance said frame forwardly on said rail, a guiding and manipulating handle extended rearwardly and upwardly from said frame, a driving motor 10 mounted on said frame, and driving gearing on said frame driven by said motor and including speed reduction means operatively connected to said upper and lower driving elements to drive the same in opposite rotative directions for simultaneously advancing the apparatus and rotating the wheel.

4. In a portable car moving apparatus adapted to be disposed in an operative position in the acute angle between a railway rail and a car wheel for operative engagement with the wheel and rail to impart rolling movement to such wheel, a portable supporting frame, means for supporting and guiding said frame along a railway rail, a lower driving element rotatably

25 mounted on said frame for driving engagement with a rail upon which a car wheel is supported to advance said frame toward the wheel, an upper driving element mounted on said frame for driving engagement with the rim of such a wheel to

30 impart forward rolling movement thereto as said frame advances in a forward direction along the rail, a driving motor mounted on and extending laterally from one side of said frame, and driving gearing on said frame driven by said motor and

35 including speed reduction means, said gearing being disposed so as to extend at least in part from said frame in the opposite lateral direction to said motor to thereby substantially counterbalance the weight of said motor, and said gearing

40 being operatively connected to said upper and lower driving elements to drive the same in opposite rotative directions to simultaneously advance the apparatus in a forward direction and impart forward rolling movement to a car wheel as such

45 wheel is engaged and rotated by said upper driving element.

5. In a portable car moving apparatus adapted to be disposed in an operative position in the acute angle between a railway rail and a car wheel for operative engagement with the wheel and rail to impart rolling movement to such wheel, a portable supporting frame having guide means on the lower portions thereof for engaging the top side edges of such a rail to support and

55 guide said frame along said rail, a lower driving element rotatably mounted on said frame for driving engagement with a rail upon which a car wheel is supported to advance said frame toward said wheel, an upper driving element mounted

60 on said frame for driving engagement with the rim of such a wheel to impart forward rolling movement thereto as said frame advances in a forward direction along the rail, a guiding and manipulating handle extended rearwardly and

65 upwardly from said frame, a driving motor mounted on and extending laterally from one side of said frame, and driving gearing on said frame driven by said motor and including speed reduction means, said gearing being disposed so

70 to extend at least in part from said frame in

75 a forward direction along the rail, a guiding and manipulating handle extended rearwardly and

upwardly from said frame, a driving motor mounted on and extending laterally from one side of said frame, and driving gearing on said frame driven by said motor and including speed reduction means, said gearing being disposed so

the opposite lateral direction to said motor to thereby balance the weight of said motor, and said gearing being operatively connected to said upper and lower driving elements to drive the same in opposite rotative directions to simultaneously advance the apparatus in a forward direction and impart forward rolling movement to a car wheel as such wheel is engaged and rotated by said upper driving element.

6. In a portable car moving apparatus adapted to be disposed in an operative position in the acute angle between a railway rail and a car wheel for operative engagement with the wheel and rail to impart rolling movement to such wheel, a portable supporting frame, means for supporting and guiding said frame along a railway rail, an upper driving element rotatably mounted on said frame for driving engagement with the rim of such a wheel to impart forward rolling movement thereto as said frame advances in a forward direction along the rail, a plurality of lower driving elements rotatably mounted on said frame in rotative weight-supporting and rotation-transmitting relation with respect to said upper driving element and arranged for driving engagement with said rail to advance said frame forwardly on said rail, a driving motor mounted on said frame, and driving gearing on said frame driven by said motor and including speed reduction means operatively connected to one of said lower driving elements to drive the same in a direction such as to advance such apparatus along a rail.

7. In a portable car moving apparatus adapted to be disposed in an operative position in the acute angle between a railway rail and a car wheel for operative engagement with the wheel and rail to impart rolling movement to such wheel, a portable supporting frame having guide means on the lower portions thereof for engaging the top side edges of such a rail to support and guide said frame along said rail, lower driving means rotatably mounted on said frame for driving engagement with a rail upon which a car wheel is supported to advance said frame toward said wheel, an upper driving element rotatably mounted on said frame in rotatably supported engagement with said lower driving means and for driving engagement with the rim of such a wheel to impart forward rolling movement thereto as said frame advances in a forward direction along the rail, a guiding handle extended rearwardly and upwardly from said frame, a driving motor mounted on said frame, and driving gearing on said frame driven by said motor and including speed reduction means, and said gearing being operatively connected to said upper and lower driving elements to drive the same through force applying movements to simultaneously advance the apparatus in a forward direction and impart forward rolling movement to a car wheel as such wheel is engaged and rotated by said upper driving element.

8. In a portable car moving apparatus adapted to be disposed in an operative position in the acute angle between a railway rail and a car wheel for operative engagement with the wheel and rail to impart rolling movement to such wheel, a portable supporting frame having guide means on the lower portions thereof for engaging the top side edges of such a rail to support and guide said frame along said rail, front and rear lower driving elements rotatably mounted in spaced relation on said frame for driving engagement with a rail to impart forward advancing

movement to said frame, an upper driving element mounted on said frame in rotative engagement with said lower elements and for driving engagement with the rim of such a wheel to impart forward rolling movement thereto as said frame advances in a forward direction along the rail, a guiding handle extended rearwardly and upwardly from said frame, a driving motor mounted on said frame, and driving gearing on said frame driven by said motor and including speed reduction means, and said gearing being operatively connected to said upper and lower driving elements to drive said lower elements in one direction and said upper element in the opposite rotative direction.

9. In a portable car moving apparatus adapted to be disposed in an operative position in the acute angle between a railway rail and a car wheel for operative engagement with the wheel and rail to impart rolling movement to such wheel, a portable supporting frame having guide means on the lower portions thereof for engaging the top side edges of such a rail to support and guide said frame along said rail, front and rear lower driving elements rotatably mounted in spaced relation on said frame for driving engagement with a rail to impart forward advancing movement to said frame, an upper driving element mounted on said frame in rotative engagement with said lower elements and for driving engagement with the rim of such a wheel to impart forward rolling movement thereto as said frame advances in a forward direction along the rail, a guiding handle extended rearwardly and upwardly from said frame, a driving motor mounted on said frame, driving gearing on said frame driven by said motor and including speed reduction means, and said gearing being operatively connected to said upper and lower driving elements to drive said lower elements in one direction and said upper element in the opposite rotative direction, and control means for said driving motor located in an accessible position on said guiding handle.

10. In a portable car moving apparatus adapted to be disposed in an operative position in the acute angle between a railway rail and a car wheel for operative engagement with the wheel and rail to impart rolling movement to such wheel, a portable supporting frame, means for supporting and guiding said frame on a railway rail for movement therealong, an upper toothed wheel rotatably mounted on said frame for driving engagement with the rim of such a wheel to impart forward rolling movement thereto as said frame advances in a forward direction along the rail, a plurality of lower toothed wheels rotatably mounted on said frame and arranged for driving engagement with said rail to advance said frame forwardly on said rail, said upper toothed wheel being meshed with both of said lower toothed wheels to act as an idler gear therebetween, a driving motor mounted on said frame and operatively connected to one of said lower toothed wheels to drive said lower toothed wheels in one direction for advancing the frame along a rail and to simultaneously drive the upper toothed wheels in the other direction for imparting rolling movement to a car wheel.

11. In a portable car moving apparatus adapted to be disposed in an operative position in the acute angle between a railway rail and a car wheel for operative engagement with the wheel and rail to impart rolling movement to

such wheel, a portable supporting frame, means for supporting and guiding said frame on a railway rail for movement therealong, a pair of spaced lower driving elements rotatably mounted on said frame and arranged for driving engagement with said rail to advance said frame forwardly on said rail, an upper driving element rotatably mounted on said frame for limited lateral shifting movement and rested upon and supported by said pair of lower driving elements and for driving engagement with the rim of such a wheel to impart forward rolling movement to such wheel as said frame advances in a forward direction along the rail, and actuating means mounted on said frame and operatively connected to said upper and lower driving elements to rotate the same in opposite rotative directions for simultaneously advancing the frame along a rail and imparting rolling movement to a car wheel.

12. In a portable car moving apparatus adapted to be disposed in an operative position in the acute angle between a railway rail and a car wheel for operative engagement with the wheel and rail to impart rolling movement to such wheel, a portable supporting frame, means for supporting and guiding said frame on a railway rail for movement therealong, an upper driving element rotatably mounted on said frame for limited radial shifting movement and for driving engagement with the rim of such a wheel to impart forward rolling movement thereto as said frame advances in a forward direction along the rail, lower rotatable driving means mounted on said frame in rotative supporting relation to said upper rotative element and arranged for driving engagement with said rail to advance said frame forwardly on said rail, and actuating means on

said frame and operatively connected to said upper and lower driving elements to drive the same in opposite rotative directions for simultaneously advancing the apparatus and rotating the wheel.

- 5 13. In a portable car moving apparatus adapted to be disposed in an operative position in the acute angle between a railway rail member and a car wheel member for operative engagement with the wheel member and rail member to 10 impart rolling movement to such wheel member, a portable supporting frame, means for supporting and guiding said frame on a railway rail member for movement therealong, a first toothed wheel rotatably mounted on said frame for driving engagement with one of said members and a pair of spaced toothed wheels rotatably mounted on said frame and arranged for concurrent driving engagement with the other of said members, said first toothed wheel being meshed with each 15 of said pair of toothed wheels to act as an idler gear therebetween, a driving motor mounted on said frame and operatively connected to one of said toothed wheels to drive said pair of toothed wheels in one direction and through said concurrent driving engagement to simultaneously drive said first toothed wheel in the other direction to thereby simultaneously advance the apparatus along the rail member and rotate the car wheel member.
